(57) **CLAIM**

We claim the ornamental design for a LED dock light head, as shown and described.

DESCRIPTION

FIG. 1 is a perspective view of a LED dock light head.

FIG. 2 is a front view of the LED dock light head shown in FIG. 1.

FIG. 3 is a rear view of the LED dock light head shown in FIG. 1.

FIG. 4 is a right side view of the LED dock light head shown in FIG. 1.

FIG. 5 is a left side view of the LED dock light head shown in FIG. 1.

FIG. 6 is a top view of the LED dock light head shown in FIG. 1; and,

FIG. 7 is a bottom view of the LED dock light head shown in FIG. 1.

The broken lines show portions of the LED dock light head that form no part of the claimed design.
